UNITED STATES PATENT OFFICE.

CHARLES T. BOYD AND GEORGE S. HERSHEY, OF COLUMBUS, OHIO.

POWDER PUFF.

Application filed September 30, 1922. Serial No. 591,624.

To all whom it may concern:

Be it known that we, CHARLES T. BOYD and GEORGE S. HERSHEY, citizens of the United States, residing at Columbus, in the 5 county of Franklin and State of Ohio, have invented a certain new and useful Improvement in Powder Puffs, of which the following is a specification.

The object of this invention is to provide 10 a powder puff for toilet use having a magazine and improved means whereby the discharge and distribution of the powder is more economically and satisfactorily controlled.

15 The invention is embodied in the example herein shown and described, the features of novelty being finally claimed.

In the accompanying drawing—

Figures 1, 2 and 3 show respectively 20 metric sections of the distributing fabric, the feeding support for the fabric and the magazine.

Fig. 4 is a similar sectional view showing said elements assembled.

25 Fig. 5 is a similar view showing a modification.

In the several views 6 designates the magazine in which the powder is placed. The magazine is preferably in the form of a circular box of sheet metal. The support 7 for 30 the distributing fabric 11 is of concavo-convex form and of resilient material—for example—rubber such as is used in the manufacture of hollow rubber balls.

35 The support 7 is shown as made with numerous perforations for the exit of the powder to the fabric. The distributing fabric 11 may be of any sort suitable for the purpose such for example as an ordinary pile 40 fabric, velour for example.

In assembling the parts according to Fig. 4 the fabric is placed over the support and the edges of the two united and secured together in a circular metallic binding ring 8 45 of U-form in cross section the lips of the ring being pressed to pinch or clinch the margins. The U-shaped ring is of such dimensions when binding the fabric and its support that it fills internally the rim of the magazine so as to form a closure therefor like the cover of a box and prevents uncontrolled exit of the powder. To facilitate the removal of the distributor and its support from the magazine there can be secured at 50 diametrically opposite points in the U-

shaped ring along with the edges of the support and fabric two short pieces of tape 9 that may be conveniently grasped to pull the ring with its support and distributor out of the magazine. The occasion for removing the parts referred to is to open the magazine to put in a new supply of powder. The distributor and its base can be permanently united as by glue or vulcanization around the unperforated margin or otherwise and 40 permanently attached to the magazine as indicated in Fig. 5 and the magazine provided with an opening in its bottom for supplying the fresh powder thereto, said opening being closed by a removable screw cap 10.

In practice the powder is expelled from the magazine by gently pressing the puff at its distributing side upon the skin (as of the face). This pressing action causes the egress of air and powder from the magazine and the reaction from the pressure draws in air. When the powder is expelled through the perforations of the resilient member by the pressure described some of it is collected in the fabric from which it 50 may be spread over the skin by the usual movements given a powder puff. With our invention there is no appreciable leakage or waste of the powder and its distribution over the skin can be very satisfactorily controlled. 55 The structure as described can be conveniently associated with a small mirror or other devices useful in making a toilet and the forms of the parts are susceptible of modification without departing from the gist of 60 the invention as claimed.

What we claim is:

1. A powder puff comprising, in combination, a magazine for the powder and a powder distributing member of resilient material attached to the magazine to receive powder therefrom.

2. A powder puff comprising, in combination, a magazine for the powder and a powder distributing member of resilient material of concavo-convex form connected with the magazine to receive the powder therefrom.

3. A powder puff comprising, in combination, a magazine for the powder and a resilient powder distributing member of concavo-convex form removably connected with the magazine to receive the powder therefrom.

4. A powder puff comprising, in combina-

tion, a magazine for the powder and a distributing member for the powder comprised of a perforated support of resilient material surmounted with powder distributing fabric, 5 said distributing fabric adapted for attachment to the magazine.

5. A powder puff comprising, in combination, a magazine of rigid material for the powder and a powder distributing member

of resilient material attached to the magazine and receiving the powder therefrom. 10

6. A powder puff comprising, in combination, a magazine of rigid material for the powder and a powder distributing member of soft rubber attached to the magazine and 15 receiving the powder therefrom.

CHARLES T. BOYD.
GEORGE S. HERSEY.
